UNITED STATES PATENT OFFICE.

LEVI J. CHAPIN, OF LUVERNE, IOWA, ASSIGNOR OF ONE-HALF TO WILLIAM E. McDONALD, OF ALGONA, IOWA.

EXCAVATOR.

1,210,760.

Specification of Letters Patent. Patented Jan. 2, 1917.

Application filed August 23, 1916. Serial No. 116,511.

To all whom it may concern:

Be it known that I, LEVI J. CHAPIN, a citizen of the United States, residing at Luverne, in the county of Kossuth and State of Iowa, have invented certain new and useful Improvements in Excavators, of which the following is a specification, reference being had to the accompanying drawings.

This invention relates to an improved excavator and has for its primary object to provide in an excavator having a traveling bucket or dipper, automatically operated means for positively discharging or expelling the earth from the bucket and scraping the walls thereof.

It is another and more particular object of the invention to provide a swinging boom and track vertically adjustable with respect to the boom, a traveling dipper mounted upon said track and means for actuating the same, a yoke pivotally supported upon the dipper, a plunger movable within the dipper and operatively connected to the yoke, and means at the outer end of the track with which the yoke is adapted to be engaged, whereby the plunger is actuated when the dipper is moved to its discharging position and the earth positively expelled from the dipper.

It is a further general object of my invention to provide a machine for the purpose of excavating or digging ditches, which is comparatively simple in construction and light in weight and not liable to get out of order, and which may be manufactured at relatively small cost.

With the above and other objects in view, my invention consists in the novel features of construction, combination and arrangement of parts to be hereinafter more fully described, claimed and illustrated in the accompanying drawings, in which,

Figure 1 is a side elevation of an excavating machine constructed in accordance with the preferred embodiment of my invention, showing the excavating bucket or dipper at the inner end of the track; Fig. 2 is a similar view showing the dipper in its discharging position; Fig. 3 is a top plan view; Fig. 4 is a section taken on the line 4—4 of Fig. 1; Fig. 5 is a section taken on the line 5—5 of Fig. 4; and Fig. 6 is a section taken on the line 6—6 of Fig. 3.

Referring in detail to the drawings, 5

designates a suitable base or platform secured upon a frame 6. To the opposite ends of this frame, the transverse beams 7 and 8 respectively are secured, and upon the ends of the beam 7 the ground wheels 9 are suitably journaled. Convergently disposed beams 10 extend beneath the platform 5 and are also fixed to the transverse beams 7 and 8, the connected ends of said beams extending forwardly of the base 5 and having a suitable wheel truck 11 swiveled thereto. 65

To the rear ends of the beams 10, uprights 12 are securely bolted at their lower ends, the upper ends of said uprights being connected by a transverse beam 13. Brace rods 14 are connected to the ends of this transverse beam and to the beam 7. To the rear end of the frame 6, upwardly converging bars 15 are fixed at their lower ends and a brace rod 16 connects the upper ends of these bars to the center of the transverse beam 13. A vertical bolt 17 is centrally fixed in the transverse beam 7, and upon the upper end thereof of a metal plate 18 is loosely engaged, the ends of said plate being formed with upwardly projecting ears 19. To these ears, 70 the lower ends of the spaced bars 20 of a swinging boom are connected. A spacing block is arranged between the upper ends of said bars and securely fixed thereto. A brace rod 21 is also connected to the free end 85 of the boom at one of its ends and to the transverse beam 13 at its other end. An inverted U-shaped plate is also loosely engaged upon the upper end of the bolt 17, and between the spaced ends of said plate the lower 90 ends of the spaced track rails 22 are pivotally mounted. Upon the pivot bolt 23 and between the spaced track rails, a guide sheave 24 is loosely engaged. The other ends of the track rails are upwardly curved, 95 as indicated at 25, and between the same one end of a spacing block 26 is fixed by means of the bolt indicated at 27, which projects beyond the opposite sides of the track for a purpose to be later explained. A sheave 100 or pulley 28 is also mounted in the block 26 and a bail 29 is pivotally connected at its ends to said block. In the spacing block, 105 between the bars 20 of the boom, a guide sheave 30 is mounted. One end of a cable 31 is attached to the bail 29 and extends over the sheave 30. The other end of this cable is attached to a drum 32, the shaft of which

is mounted between the upper ends of the spaced standards 33. One end of the drum shaft is provided with a suitable crank 34 which is adapted to be engaged and held by 5 a suitable latch member 35 which is suitably mounted upon the beam 13. By means of the cable 31, it will be readily understood that the track may be raised or lowered and disposed at any desired inclination.

10 36 designates the bucket or dipper which is preferably constructed from a single sheet metal plate, the ends of which are riveted or otherwise secured together and extended upwardly between the track rails, as shown at 15 37. Spaced rollers 38 arranged in pairs are disposed above and below the respective track rails and mounted upon stud bolts 39 fixed in the ends of the dipper plate. These bolts are connected by the strap bars 40 which retain the rollers in position thereon. To the opposite ends of the upwardly projecting portion of the bucket, spaced rods 41 are securely riveted at one of their ends and connected together at their other ends by the bolt 42. Between the connected ends of said rods, a sheave 43 is mounted upon said bolt, and the arms of an elongated yoke 44 are also loosely engaged upon the opposite ends of the bolt. The yoke arms extend 20 downwardly upon opposite sides of the track rails, and between the extremities of said arms the end of a plunger rod 45 is loosely engaged upon the bolt 46 connecting the yoke arms. The plunger head 47 fixed to 25 the other end of said rod, operates within the rectangular bucket or dipper 36. To one end of the bucket, a cable 48 is attached and extends upwardly around the sheave or pulley 28 mounted in the block 26, and then 30 over the pulley 42, and has its other end connected to a second drum 49 mounted between the spaced standards 33. The shaft of this drum is also provided with a suitable crank 50 which may be held against operation 35 by the latch member 51. The cable 52 is also connected at one of its ends to the other end of the bucket or dipper 36 and extends under the guide sheave or pulley 24 and over a second guide pulley 52' mounted 40 between the standards 33, and has its other end connected to a third drum 54 rotatably mounted between said standards. The shaft of this drum likewise has an operating crank 53. To the bottom of the dipper, at its inner end, the dipper knife 55 is riveted or 45 otherwise secured, said knife being of greater width than the bucket and projecting beyond the opposite sides thereof.

50 Obliquely disposed bars 56 are securely bolted or otherwise mounted upon the frame 6 and the uprights 12, and upon these bars a shaft 57 is rotatably mounted. Upon the ends of this shaft, drums 58 are fixed, and cables 59 are attached at one of their ends to 55 said drums and extend around guide sheaves

60 on the bars 56 and are attached at their other ends to the swinging boom. A gear wheel 61 is also secured upon the shaft 7 and a pinion 62 which is fixed upon a shaft 63 mounted upon one of the standards 33, 70 meshes with said gear. This shaft has a suitable crank 64 on one end, whereby the same may be conveniently operated. It will be understood that, in the rotation of the shaft 57 in either direction, one cable will be 75 wound upon one of the drums 58 while the other cable will unwind from the other drum and the boom will be swung laterally in the desired direction.

In the operation of the machine as above 80 described, when the bucket or dipper is drawn inwardly upon the supporting track which has been properly adjusted with respect to the boom, the dipper knife cuts into the earth which enters the bucket, and as it 85 accumulates therein forces the plunger in said bucket longitudinally toward the opposite end of the bucket. When the bucket reaches the inner end of the track, it is filled with earth, and the outer end of the track is 90 then raised. The cable connected to the outer end of the bucket is then wound upon its drum and the bucket pulled or drawn outwardly upon the track and upwardly upon the curved end of the track rails. The 95 arms of the yoke 44 are thus brought into contact with the projecting ends of the bolt 27 and the plunger connected to the yoke arms is forced inwardly and downwardly through the dipper to positively expel or 100 discharge the earth therefrom, and scrape or clean the dipper walls. In this manner, it will be seen that all of the earth is positively ejected so that a full load is discharged in 105 each operation.

Upon the base or platform 5, a drum 65 is suitably mounted and has a sprocket 66 on one end to receive a drive chain operated from the engine shaft 67. The other end of said drum is provided with a ratchet 68 for engagement by a gravity pawl 69, whereby the drum is securely held against rotation in one direction. A cable 70 extends beneath the platform and is attached at one of its ends to the drum. This cable 110 is of considerable length and is suitably anchored at its other end. Thus, as the work progresses, the cable 70 may be wound upon the drum to move the machine from one place to another.

115 From the foregoing description, taken in connection with the accompanying drawings, the construction, manner of operation and several advantages of my invention will be clearly and fully understood.

120 The machine as a whole is comparatively simple and will require but few and infrequent repairs. It is manifest, of course, that the bucket or dipper may be of any desired capacity and the size and relative 125 130

proportions of the concomitant parts varied accordingly. The machine is also susceptible of considerable modification in the form, proportion and arrangement of the several elements employed and I, therefore, reserve the privilege of adopting all such legitimate changes as may be fairly embodied within the spirit and scope of the invention as claimed.

10 Having thus fully described my invention, what I desire to claim and secure by Letters Patent is:—

15 1. In an excavating machine, a vertically swinging track, a dipper mounted to travel upon the track and suspended therefrom, means for moving the dipper, a plunger longitudinally movable in the dipper having a rigid rod projecting from one end of the dipper, a rigid actuating element pivotally supported upon the dipper above the track and operatively connected to the plunger rod, and means on one end of the track with which said element is adapted to engage in the movement of the dipper to its discharging position, whereby the plunger is actuated and the earth expelled from the dipper.

20 2. In an excavating machine, a track, a dipper suspended from said track for longitudinal movement thereon, means for operating the dipper, a plunger longitudinally movable in the dipper, actuating means pivotally mounted upon the dipper above the track and operatively connected to the plunger, and a fixed stop element on the track at one end thereof adapted to be engaged by said actuating means to

move the plunger and expel the earth from the dipper.

25 3. In an excavating machine, a vertically swinging track having an upwardly curved free end portion, a dipper to travel upon said track, means for moving the dipper, a stop fixed to the curved end of the track, a plunger longitudinally movable in the dipper, and an actuating element pivotally mounted upon the dipper and operatively connected to the plunger, said element engaging said stop when the dipper is moved to its discharging position on the curved end of the track to move the plunger and positively expel the earth from the dipper.

30 4. In an excavating machine, a vertically swinging track having an upwardly curved free end portion, a dipper to travel upon said track, means for moving the dipper, a stop fixed to the curved end of the track, a plunger longitudinally movable in the dipper, and a yoke member pivotally mounted upon the dipper, the arms of said yoke member straddling the track being operatively connected to the plunger, said yoke arms engaging the stop when the dipper is moved to a discharging position upon the curved end of the track to positively actuate the plunger and expel the earth from the dipper.

35 In testimony whereof I hereunto affix my signature in the presence of two witnesses.

LEVI J. CHAPIN.
